UNITED STATES PATENT OFFICE.

ALLISON N. CLARK, OF PLAINVILLE, CONNECTICUT.

IMPROVEMENT IN COMPOUND POCKET IMPLEMENTS.

Specification forming part of Letters Patent No. 155,790, dated October 13, 1874; application filed February 20, 1874.

To all whom it may concern:

Be it known that I, ALLISON N. CLARK, of Plainville, in the county of Hartford and State of Connecticut, have invented a new and Improved Pocket Implement, containing an ear-spoon, &c., of which the following is a specification:

In my improved pocket implement a single shaft, with an ear-spoon at one end and a watch-key at the other, is pivoted between a pair of spring-jaws, which have curved faces, after the manner of a well-known spring-joint. The pieces forming the spring-jaws are long enough to form two pairs of spring-jaws, and are rigidly secured together between their ends, all as hereafter described.

In the accompanying drawing, Figure 1 is an edge view of an improved pocket implement, which embodies my invention; and Fig. 2 is a side view of the same.

a b designates a shaft, the end *a* of which is provided with a square hole, thus forming it into the pipe of a watch-key. The end *b* of the shaft *a b* is formed into an ear-spoon. *c c* designates two pieces of spring steel, which are preferably formed from sheet metal, and struck up in dies into the form shown. These pieces are connected midway between their two ends to a post, *d*. I prefer to make a flat tenon at each end of the post *d*, and secure it in a hole of a corresponding shape made in the pieces *c c* by upsetting the ends of the tenons.

If desired, the post *d* may be wholly omitted, and a portion of each of the pieces *c c* swaged inward, so that when the inwardly-swaged parts are riveted together the pieces upon each side of the connection will be open, and form spring-jaws at each end, and the

same as if secured together by the post *d*. The faces of the pieces *c c* at one end are concave, and the shaft *a b* is pivoted therein, after the well-known manner of pivoting a pocket cork-screw in spring-jaws, and the other ends of the pieces *c c* are of such form as to constitute a pair of spring-tweezers. When the end *a* of the shaft *a b* is outward the implement constitutes a watch-key, the end *a* forming the pipe, and the tweezers on one end of the pieces *c c* forms the handle of the key, and if the end *b* is outward the device is converted into an ear-spoon, the same part forming the handle as when it is used as a watch-key.

If desired, instead of a watch-key and ear-spoon, other convenient pocket-tools may be substituted therefor, and hung between the spring-jaws, as herein described.

I do not claim a swivel-shaft pivoted between spring-jaws; neither do I claim a combination implement, consisting of the aggregation of tweezers, ear-spoon, and watch-key; but

What I claim as my invention is—

In a pocket implement, consisting of tweezers, ear-spoon, and watch-key, as described, the spring pieces *c c*, constructed as shown and described, and connected together between their ends, thus forming a pair of spring-jaws upon each side of said connection, one of which jaws is provided with the swivel-shaft *a b*, all substantially as set forth.

ALLISON N. CLARK.
